UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

GRAVITY COOLING DEVICE FOR STEREOTYPE-PLATES.

1,150,475.

Specification of Letters Patent.

Patented Aug. 17, 1915

Original application filed August 9, 1906, Serial No. 329,833. Divided and this application filed October 2 1913. Serial No. 792,984.

To all whom it may concern:

Be it known that I, HENRY A. WISE Wood, a citizen of the United States, residing at New York, in the county of New York and State of New York, have invented a new and useful Gravity Cooling Device for Stereotype-Plates, of which the following is a specification.

This invention relates to improvements in 10 machines for cooling and drying stereotype plates in which the latter are fed partially or wholly by gravity down an inclined plane while various operations are performed.

In a previous application for patent on a 5 "Machine for finishing and cooling stereotype plates," filed April 6, 1906, Serial No. 310,343, I have described an invention on which this is an improvement.

The principal objects of this improvement 20 are to provide means for commencing the cooling operation at an earlier period and carrying it on continuously; to provide more efficient means for rapidly cooling the plate; to provide for removing the free water from 25 both the inside and outside of the plate in such a manner as to leave the printing surface in a condition sufficiently dry for immediate attachment to the press; and to generally improve and simplify the construction 30 of machines of this type.

It is to be understood that while I have illustrated and described an embodiment of the invention in which it is employed for use upon stereotype plates and while that is 35 the principal use to which I at present contemplate putting it, yet the principles involved are applicable for operation upon other kinds of castings and articles which have to be cooled or dried.

Reference is to be had to the accompanying 40 three sheets of drawings in which,

Figure 1 is a side elevation of a machine illustrating one embodiment of my invention: Fig. 2 is a side elevation of a portion 45 of the same on an enlarged scale, parts appearing in section: Fig. 3 is a fragmentary plan of a portion of the same: Fig. 4 is a sectional view on the line 4-4 of Fig. 3: and, Fig. 5 is a sectional view on the line 50 5-5 of Fig. 3.

In a machine of this type, a frame *a* is provided having an inclined body or run-

way *a'* for supporting and carrying stereotype plates or the like. The machine is intended to be used in conjunction with an 55 arch *c* in which their interior surfaces are shaved. From this point they pass to a cooler *d* and from that they move out on a table *e* from which they are removed by hand or otherwise.

It is to be observed that on account of the incline of the runway and on account of the fact that it is provided with anti-friction devices shown in the form of a series of rollers 20, no positive feeding mechanism and 60 no driving device for feeding the plates or other blanks is necessary. The incline of the bed is such that the plates are readily fed down by gravity when they rest freely on the rollers.

The mechanism so far described, is shown broadly in the application referred to above. In the present case, in addition to the general features indicated by the reference letters, the machine is provided with a drying 75 device *f* adapted to remove the free water from the surfaces of the plate after it passes through the cooler and in addition to this, the arch *c*, in which the shaving is performed, is provided with means for preliminarily cooling the plates while they are being shaved so as to commence the cooling 80 earlier and thus insure the desired drop in temperature by the time the plates reach the drying device. These features and other 85 principles which I have employed for the purpose of improving the type of gravity shaving machine represented in the above mentioned application, will now be described by reference to the construction which is 90 illustrated in the drawings.

The main shaft 31 carries a worm 38 which operates a worm-wheel 39 on a shaft 26. Arranged on this shaft is a shaving blade 40 located in the arch *c*. The plate descends along the inclined table into this 95 arch and is stopped in proper position therein by means of mechanism operated from the shaft 26. While the plate is in the arch *c*, it is intended to be cooled simultaneously 100 with the shaving operation. For this purpose the arch is hollow or has a channel 68, as shown in Fig. 2, this being provided with a supply pipe 69 at one end and a discharge

pipe 70 at the other. When the plate reaches the proper position in the arch d , it is stopped by a gate 21^a. A shield 71 is provided to prevent spattering of water from the cooler on the machine.

In the upper part of the arch d is a pipe 72 which preferably receives water from the pipe 70 and which is provided with perforations for directing the water on the top of the stereotype plate while the latter is in the arch. In order to provide conveniently for this pipe, the arch has a channel 73 in the upper part thereof in which the pipe is located. Lower down in the arch is a plate 74 of a shape similar to that of the stereotype plate and located in such position that the plate passes over it. This plate 74 also has a cavity 75 in which is located a pipe 76 having perforations for directing the water therefrom against the under side of the stereotype plate. The pipe 76 receives water from the pipe 70. It will be seen that the water forced against the plate on both sides will run down the same into a trough 77 located below from which it discharges through a pipe 78. A second splash guard 79 is located below the arch d . When the cooling operation is completed, the cam for operating the stop 21^a moves into such position that the gate is withdrawn and the plate is allowed to feed along by gravity into the drying device. This drying device comprises a frame 80 having a series of adjustable bearings 81 supported by springs 82 and adjusted by thumb nuts 83. Each pair of bearings supports a roller 84 covered by absorbent gauze or other absorbent material. These rollers are of such a longitudinal cross-section that their outer surfaces form the arc of a circle of the same radius as that of the stereotype plate and their edges meet so that the entire surface of the plate is operated upon by the rollers to remove the free water therefrom, which otherwise would damage the inking rollers of the press. The frame 80 is movably mounted on the main frame a so that the whole device can be quickly removed bodily for the purpose of replacing the rollers with dry ones to insure nearly perfect action.

For the purpose of brushing the moisture and incidental metal shavings from the interior of the plate, the shaft 26 is provided with an arm 85 having a pin 86 which rotates with it. On a shaft 87 placed somewhat eccentric with respect to shaft 26 is an arm 88 having a slot 89 in which the pin 86 operates. Such a connection is required because of the eccentric relation of the shafts. Adjustably mounted with respect to the arm 88 is a frame 90 carrying a brush 91, extending the length of the stereotype plate, adapted to be turned by the rotation of the shaft 26 so as to clean and dry the interior surfaces of the plates. As a plate

passes under the outside drying device, it moves to a position above the table over the drying and cleaning brush and can be removed therefrom by hand or forced from the position over the brush by the descent 70 of the next plate from above or by gravity.

By the employment of the principles illustrated above, whether in the form shown or in any other form embodying these principles, it will be seen that the stereotype plates 75 are fed along the machine in a most effective and inexpensive manner by gravity; that the plates are cooled in a most effective manner by direct contact with water and are finally wiped and dried both on the inside and on 80 the outside, and that the machine is improved and simplified in many particulars.

While I have shown and described a particular form in which I at present prefer to embody my invention, I am aware of the 85 fact that many changes can be made therein by any person skilled in the art without departing from the principles of my invention or from the scope thereof as expressed in the claims. Therefore, I do not wish to be 90 limited to the particular mechanism illustrated and described, but

What I do claim and desire to secure by Letters-Patenet is:-

1. In a machine for finishing and cooling 95 cast plates, the combination of a cooling arch through which the plates pass, and a stationary splash plate located on each side of the cooling arch.
2. In a machine for cooling cast plates, 100 the combination of a longitudinal perforated pipe for directing a cooling fluid against the outside of the plates with a pipe for simultaneously directing a cooling fluid against the inside of the plates.
3. In a machine for cooling cast plates, 105 the combination of an arch for receiving the plates, means for directing cooling fluid on both sides of a plate in the arch, and means beneath the arch for receiving the cooling 110 fluid discharged, said arch having oppositely facing troughs for receiving the fluid directing means.
4. In a machine for cooling cast plates, the 115 combination of means for wetting the cast plates, and means for subsequently removing from them the free water remaining thereon.
5. In a machine for cooling cast plates, the 120 combination of means for directing water against the upper and lower surfaces of the cast plates, and means for subsequently removing the free water from both of said surfaces.
6. In a machine for cooling cast plates, 125 the combination of means for directing water against the upper surfaces of the plates, means for directing water against the lower surfaces of the plates, means for wiping the free water from the upper sur- 130

- faces of the plates, means for brushing the lower surfaces of the plates, and a gravity feed device for transferring the plates from the two water directing means to the wiping 5 and brushing means.
7. In a machine for cooling cast plates, the combination of means for directing water against the upper surfaces of the plates, means for directing water against the lower 10 surfaces of the plates, means for wiping the free water from the upper surfaces of the plates, and means for brushing the lower surfaces of the plates.
8. In a machine for preparing stereotype 15 plates for printing, the combination of means for applying water to the surfaces of the plates, and a series of rollers having absorbent material for removing the water from the plates.
9. In a machine for preparing stereotype 20 plates for printing, the combination of means for applying water to the surfaces of the plates, a series of rollers having absorbent material for removing the water 25 from the plates, and a movable brush for operating on the insides of the plates.
10. In a machine for preparing stereotype 30 plates for printing, the combination of means for preliminarily cooling the plates, means for completing the cooling of the plates by the application of water directly to the surfaces thereof, and means for removing the water from the plates.
11. In a machine for preparing stereotype 35 plates for printing, the combination of means for preliminarily cooling the plates, means for completing the cooling of the plates by the application of water directly to the surfaces thereof, means for removing 40 the water from the plates, and a gravity feed device for transferring the plates automatically through said several devices in the order named.
12. The combination with means for preliminarily cooling plates out of contact with the cooling fluid, of means for thereafter applying a cooling fluid to the plates, and means for feeding plates to the device.
13. The combination with means for preliminarily cooling plates out of contact with the cooling fluid, of means for thereafter applying a cooling fluid to the plates, means for feeding plates to the cooling device, and means for removing the plates therefrom.
14. The combination of an arch for receiving the plate, means for preliminarily cooling the plate while in said arch without direct contact with the cooling fluid, a cooling arch having means for carrying forward 50 the cooling of the plates, and means for directing the plate from the first mentioned arch to the cooling arch.
15. The combination of an arch for receiving the plates, means for preliminarily cooling the plates in the arch, and means for 55 carrying forward the cooling of the plates after they are discharged from the arch.
16. The combination of an arch for receiving the plates, said arch having means for preliminarily cooling the plates, and a cooling arch into which the plates are discharged from the first mentioned arch, said cooling arch having means for directing a cooling fluid against the plates, and carrying forward the cooling operation. 70
17. In a stereotype plate mechanism, the combination of means for cooling the plates, means for drying the plates, and means for carrying the plates from the cooling means to the drying means. 75
18. In a stereotype plate mechanism, the combination of means for cooling the plates, means for drying the plates, means for carrying the plates from the cooling means to the drying means, and means for supporting the plates after drying. 80
19. In a plate machine, the combination of a holder for receiving the plates, means for preliminarily cooling the plates in the holder, and means for carrying forward the cooling of the plates after they are discharged from the holder. 85
20. In a machine for preparing stereotype plates for printing, the combination with means for wetting the plates to cool them, of means for thereafter wiping the water from the plates. 90
21. In a machine for cooling cast plates, the combination of means for preliminarily cooling the plates, a cooling device in position to receive plates, means in the cooling device for directing a cooling fluid against the plates and carrying forward the cooling operation, and a trough connected with said cooling device for receiving the discharged fluid from the cooling device. 100
22. In a plate cooling machine, the combination of means for preliminarily cooling plates, a feeding device, a splash plate, and means beyond the splash plate for receiving the plates and carrying forward the cooling operation. 110
23. A machine for preparing stereotype plates for printing, comprising a support for the plates and a series of rollers of absorbent material carried by said support in position for removing water from the plates when the plates are on the support. 115
24. A machine for preparing curved stereotype plates for printing, comprising a substantially semi-circular frame, and a plurality of absorbent rollers thereon, said rollers having surfaces constituting a semi-circular substantially continuous surface for engaging said plates. 120
25. In a machine for preparing curved stereotype plates for printing, the combination of a frame having a plurality of absorbent rollers mounted thereon, each of said rollers having a longitudinally curved sur- 125
- 130

face, and all of said rollers together constituting a continuous wiping device for the plates.

26. A machine for preparing stereotype plates for printing, comprising a plurality of absorbent rollers arranged with their ends in contact with each other and with their operating surfaces having a configuration substantially of the same shape as the cross-section of a plate to be treated.

27. In a machine for preparing stereotype plates for printing, the combination of a frame, a series of absorbent rollers movably mounted thereon, and means for adjusting the position of said rollers.

28. In a machine for preparing stereotype plates for printing, the combination of a main frame, a supplementary frame removably mounted thereon, and a series of absorbent drying devices mounted on said supplementary frame.

29. In a machine for preparing stereotype plates for printing, the combination of absorbent means for removing water from the

outer surfaces of the plates, and a movable brush for cleaning the inner surfaces of the plates.

30. In a machine for preparing stereotype plates for printing, the combination of a stationary frame, rotary absorbent members movably mounted on said frame and having their axes perpendicular to the axes of the stereotype plates in the machine, and a movable brush mounted to engage the inner surfaces of the plate.

31. A machine for preparing curved stereotype plates for printing, comprising a brush mounted to turn on an axis parallel with the axis of the plates, and adapted to operate on the interior surfaces thereof.

In testimony whereof I have hereunto set my hand, in the presence of two subscribing witnesses.

HENRY A. WISE WOOD.
